UNITED STATES PATENT OFFICE.

EDWARD J. BROOKS, OF EAST ORANGE, NEW JERSEY.

BUNG-TIN DRIVER.

No. 822,918.

Specification of Letters Patent.

Patented June 12, 1906.

Application filed April 18, 1905. Serial No. 256,254.

To all whom it may concern:

Be it known that I, EDWARD J. BROOKS, a citizen of the United States of America, and a resident of East Orange, in the State of New Jersey, have invented a new and useful Improvement in Bung-Tin Drivers, of which the following is a specification.

This invention relates to means for fastening or driving what are known as "bung-tins," which are usually employed to supplement and secure ordinary wooden bungs after they have been driven into the bung-holes of wooden barrels, half-barrels, kegs, and the like to prevent the bungs from being accidentally pressed out or loosened, which occurs very often in shipping liquors, &c., when the bungs are not thus secured. Such bung-tins are or may also be employed, in connection with one or more thicknesses of heavy cloth or paper beneath them, as substitutes for bungs; but generally it is best to have a suitable bung within the bung-hole in addition to the bung-tin.

The present invention consists in an improved bung-tin driver embodying a novel combination of parts hereinafter set forth and claimed.

The objects of this invention are to simplify the construction of the bung-tin driver, to adapt the same to be made wholly of metal with a single spring of ample capacity, and to facilitate its adaptation to bung-tins of any desired shape, as round, square, or triangular, the preferred form being round.

35 A sheet of drawings accompanies this specification as part thereof.

Figure 1 is a perspective view of the improved bung-tin driver. Fig. 2 is a like view of a bung-tin adapted to be driven by means 40 of the same. Fig. 3 is a face view of the bung-tin driver, showing a bung-tin in place within it; and Fig. 4 is a section on the line A' B', Fig. 3.

Like reference characters refer to like parts 45 in all the figures.

The bung-tin A in the form represented in Figs. 2, 3, and 4 has a circular disk of suitable tin (tin-plate) with downturned marginal edges a, terminating at a sufficient number of points in sharp spurs a', which, together with said downturned rim, are driven into the wood of the barrel (represented at B in Fig. 4) around the bung-hole b and bung C by means of the bung-tin driver. The tin 55 may be of other shapes, as above indicated,

and may, if desired, bear distinguishing marks or lettering.

The bung-tin driver consists of an outer part 1, the lower edge d of which is adapted to rest upon the barrel around the bung-hole, 60 as represented in Fig. 4; an annular plunger 2 within the main recess e of said outer part; a central longitudinal stem 3, rigidly united with said plunger 2 and extending upwardly within a sleeve portion f of said outer part, 65 which also forms a convenient handle; an open helical spring 4 within said sleeve portion f above an inwardly-projecting flange g at mid-height within the latter; an impact-cap 5, attached to the upper end of said stem 3 and forming an annular shoulder h around the same against which said spring 4 reacts, and means for uniting said plunger 2, stem 3, and cap 5 with each other, said means including a removable transverse pin 6, extending through said cap 5 and through the upper end of said stem 2, as shown in Fig. 4. By removing said pin 6 said cap 5 may be detached, and the plunger 2 and stem 3 will then drop from within the outer part 1, and 80 the spring 4 may be removed upwardly, so as to facilitate renewing said cap 5 and said spring 4, which are the only parts subjected to wear.

The outer part 1, as above described, may be readily formed complete as a casting of 85 suitable metal and readily finished by milling the same internally. The plunger 2 may also be a casting, with a central opening j to receive the lower end of the stem 3, surrounded on top by a crown-flange k, through which a 90 radial screw 7 may extend into a peripheral stop-flange l near the lower end of the stem. This flange l is formed on a sleeve 8, that is shrunk fast on the lower end of the stem proper, so that the latter may conveniently 95 be made of bar iron or steel of one and the same smaller diameter throughout its length.

The recess e at the lower end of the outer part 1 and the plunger 2 correspond in shape, as viewed in Fig. 3, with the bung-tin A, and 100 the face of the plunger 2 is preferably concaved, so as to locate its pressure upon the bung-tin directly above the flange a and spurs a' of the latter, and thus to insure an effective concentration of the driving energy. 105 (See Fig. 4.)

The capped upper end of the driver may be struck by any convenient hammer or mallet, and the blows serve to compress the spring 4 of the driver and to force the plunger into its 110

lowermost position, which in turn forces the spurs a' and flange a of the tin A into the wood of the barrel B around the bung-hole and effectively secures the bung C or its equivalent in place.

5 The external shape of the outer part 1 may of course vary, as well as the shape of its recess e , and other like modifications will suggest themselves to those skilled in the art.

10 Having thus described said improvement, I claim as my invention and desire to patent under this specification—

15 The combination, in a bung-tin driver, of an outer part having a recess in its lower end adapted to receive a bung-tin within it, a lower edge adapted to rest upon a barrel or the like around its bung-hole, and an up-

wardly-projecting sleeve portion containing an inwardly-projecting flange at mid-height, a normally elevated plunger within said recess beneath which the bung-tin is inserted, a central stem, means for rigidly connecting said plunger and stem including a shoulder-forming sleeve within said sleeve portion beneath said flange, an upwardly-pressing spring surrounding said stem within said sleeve portion above said flange, and an impact-cap attached to the upper end of said stem and forming a shoulder around the same against which said spring reacts.

EDWARD J. BROOKS.
